UNITED STATES PATENT OFFICE.

OLIVER NICHOLS, OF MOUND VALLEY, KANSAS.

COMBINED GAS AND OIL BURNER.

1,072,976.

Specification of Letters Patent.

Patented Sept. 9, 1913.

Application filed September 26, 1912. Serial No. 722,494.

To all whom it may concern:

Be it known that I, OLIVER NICHOLS, a citizen of the United States, residing at Mound Valley, in the county of Labette 5 and State of Kansas, have invented certain new and useful Improvements in Combined Gas and Oil Burners, of which the following is a specification.

This invention relates to combined gas 10 and oil burners and has for its object to produce a burner equipped with means whereby oil shall be automatically supplied to the burner in the event that the gas pressure is reduced from any cause.

15 With this general object in view, the invention consists in certain novel and peculiar features of construction and organization as hereinafter described and claimed, and in order that it may be fully understood 20 reference is to be had to the accompanying drawing, in which—

Figure 1, is a side view of a heating stove equipped with a combined gas and oil burner embodying my invention. Fig. 2, is an enlarged plan view of the burner. Fig. 3, is a central vertical section of the burner. Fig. 4, is a central vertical section of a valve for automatically opening the passage for oil to the burner in the event that the pressure of the gas is lowered from any cause.

In the said drawing, a gas receptacle of any suitable configuration is shown as composed of the body or pan portion 1 and the top or cap portion 2, the latter being formed 35 with an annular depression or channel 3 in its upper side and with a shallow diametric channel or depression 4 in that portion surrounded by the channel 3, the outer and inner walls of channel 3 being provided with 40 jet orifices 5 and 6 above the plane of the bottom of channel 4.

7 is a pipe for supplying gas to the receptacle 1, said pipe being provided with a mixer 8 of any suitable type and with a controlling valve 9. It is also provided with a branch pipe 10, communicating with one end of a casing 11, provided with inlet and outlet ports 12 and 13, and fitting slidably in said casing and normally closing said ports 50 is a valve 14, provided with an annular circumferential channel 15. The gas at normal pressure holds the valve with its channel 15 out of alignment with ports 12 and 13. To operate said valve against the pressure 55 of the gas, that is when the pressure is lowered from any cause, a spring 16 bears

against the opposite end of the valve from that adjacent pipe 10, the object of the spring being to slide the valve until its channel 15 opens communication between 60 said ports 12 and 13, for the purpose of permitting oil to pass to the burner, as herein-after explained, and in order that the pressure of the spring may be properly gaged, a set screw 17 is mounted in one end of the 65 casing 11 and forms a resistance for the adjacent end of spring 16.

18 is an oil supply tank located at a convenient point, and provided with a pipe 19 communicating with port 12, and said pipe 70 is controlled by a valve 20. A pipe 21 leads from port 13 and communicates with a T-coupling 22, to the opposite ends of which are attached oil vaporizing coils or pipes 23, the same being disposed vertically above the 75 channel of the gas receptacle 1, in such a manner that the flame from the orifices 5 and 6 shall impinge upon them, by preference, and each of said coils terminates in a depending portion 24 communicating with 80 one end of a burner pipe 25. Each of said pipes 25, is provided with a series of burner orifices 26, one series being adapted to discharge vaporized oil upon one arm of the adjacent coil and the other series upon the 85 other arm of said coil, so that the oil in the generator shall be vaporized before it reaches said burner pipe, and for the purpose of draining the surplus oil which may accumulate in the channel 3, a drain pipe 27 extends down through the receptacle from the 90 base of the channel 4 and may discharge into a suitable receptacle, not shown, below the stove 28 equipped with such burner, or at any other point.

Assuming that gas is being burned, it will be understood that its pressure holds the valve 14 in the position shown in Fig. 4, and that the gas entering the receptacle is discharged upwardly through the orifices 5 100 and 6 where it is ignited. Should the supply of gas be cut off accidentally or otherwise, the spring 16 will slide the valve 14 to the right and thus establish communication between ports 12 and 13 by way of channel 105 15 of said valve, and as this action occurs oil will pass from the tank through pipe 19, if valve 20 is open which is its normal condition, to port 12 and then pass by way of channel 15, port 13 and pipe 21 to the generator 110 23, where it is converted into vapor because such generator has been raised to

vaporizing temperature by the flame from the burning gas, the gas produced by the vaporization of the oil escaping up through burner orifices 26 and igniting from the flame from orifices 5 and 6, as under ordinary conditions the change from gas to oil will occur before the supply of gas in the receptacle is exhausted.

If desired the gas may be cut off by the valve 9, and, by proper operation of the set screw 17, valve 14 opened and oil be permitted to pass into the channel 3 and be ignited therein for the purpose of raising the generators to vaporizing temperature, and as soon as this occurs the gas thus produced and discharged from the pipes 25, continues this vaporizing action, it being obvious that if an excess quantity of oil is supplied to channel 3, the surplus will overflow into channel 4 and escape by way of the drain pipe 27. By this arrangement it is obvious that if an excess quantity of oil is supplied to channel 3, it cannot rise to the level of the orifices 5 and 6 and enter the receptacle 1 and thus pass down into the gas supply pipe 7 and out through the mixer 9 upon the floor.

From the above description, it will be apparent that I have produced a combined oil and gas burner embodying the feature of advantage enumerated as desirable, and which is susceptible of modification without departing from the principle of construction as defined by the appended claims.

35 I claim:

1. A burner, comprising a part provided with an annular oil containing channel in its upper side and a drain pipe passing through the space inclosed by said channel 40 to carry off excess liquid therefrom, a two-armed generator over the channel, and a burner pipe interposed between the bottom of the channel and the generator and communicating with the latter and provided 45 with orifices to discharge flame upwardly against the same.

2. In a burner, a feed pipe branching into two semicircular generator sections each

leading into a semicircular return section within and slightly spaced from the first 50 sections, and said return sections each leading into a semicircular burner section, each burner section being located directly beneath the space between said generator and return sections.

55

3. The combination with an oil burner, of an oil supply pipe, a spring-pressed valve in said supply pipe, said valve being normally open to permit the flow of oil through said pipe, and means for supplying to said valve gas under pressure tending to close the same and shut off the oil supply.

4. In a combined oil and gas burner, an oil supply pipe and a gas supply pipe, both pipes communicating with the burner, a 65 valve in the oil supply pipe, a spring acting upon said valve and tending to force it in a direction to open it to permit oil to flow through the oil pipe, and a branch pipe from said valve to the gas supply pipe whereby 70 pressure is applied to the valve tending to force it in a direction to close it and shut off the flow of oil in the oil pipe.

5. In a burner, a gas receptacle comprising a pan portion and a cap, the latter being provided in its upper side with an annular channel and with burner orifices in the side walls of said channel, and with a shallow channel extending below the plane of the said orifices, and across that portion 80 of the cap surrounded by the said annular channel.

6. The combination of a burner pan, a pipe communicating therewith, a top on the pan provided with an annular channel and 85 a series of holes around its border, and also with a central shallow depression communicating with the channel, and a pipe communicating at its upper end with the depression at a point below the plane of said holes. 90

In testimony whereof I affix my signature, in the presence of two witnesses.

OLIVER NICHOLS.
